[57] CLAIM

The ornamental design for a razor handle, as shown and described.

DESCRIPTION

FIG. 1 is a perspective view of a razor handle showing my new design (unclaimed environmental structure being shown in broken lines);
 FIG. 2 is a top plan view thereof (unclaimed environmental structure being shown in broken lines);
 FIG. 3 is a front elevational view thereof (unclaimed environmental structure being shown in broken lines);
 FIG. 4 is a right side elevational view thereof, the left side being a mirror image (unclaimed environmental structure being shown in broken lines);
 FIG. 5 is a rear elevational view thereof (unclaimed environmental structure being shown in broken lines); and,
 FIG. 6 is a bottom plan view thereof, (unclaimed environmental structure being shown in broken lines).

FIG. 1

FIG. 2

FIG. 3

FIG. 4

FIG. 5

FIG. 6
